Primary Examiner — Rosemary K Tarcza*Assistant Examiner* — Seth David Kumpf*(74) Attorney, Agent, or Firm* — Zhigang Ma(57) **CLAIM**

The ornamental design for an extension socket, as shown and described.

DESCRIPTION

FIG. 1 is a perspective view of an extension socket according to the present invention;

FIG. 2 is a first side view of an extension socket according to the present invention;

FIG. 3 is a second side view of an extension socket according to the present invention;

FIG. 4 is a third side view of an extension socket according to the present invention;

FIG. 5 is a fourth side view of an extension socket according to the present invention;

FIG. 6 is a top view of an extension socket according to the present invention; and,

FIG. 7 is a bottom view of an extension socket according to the present invention.

The broken lines shown in the drawings are for the purpose of illustrating portions of the extension socket and form no part of the claimed design.

1 Claim, 7 Drawing Sheets(56)
